UNITED STATES PATENT OFFICE.

CORNELIUS COLLINS, OF LOS ANGELES, CALIFORNIA.

MACHINE FOR ASSEMBLING METAL LATH UPON STUDDING ELEMENTS.

Application filed April 23, 1923. Serial No. 634,197.

To all whom it may concern:

Be it known that I, CORNELIUS COLLINS, a citizen of the United States, residing at Los Angeles, county of Los Angeles, and State of California, have invented new and useful Improvements in Machines for Assembling Metal Lath Upon Studding Elements, of which the following is a specification.

This invention relates to a machine for assembling strips or sections of metal lath upon metal studding elements.

Where expanded metal or wire mesh is used in walls, partitions, etc., it is desirable to assemble the same upon the metal studding elements before the latter are erected. By the present invention I am enabled to do this mechanically. A large roll of metal lath is placed upon the machine and studding elements with integral fastening prongs are laid upon the bed of the machine at the desired distances apart and the lath is thereupon unwound and laid upon the studding elements and the projecting prongs bent over to retain the lath in place.

One form which my invention may assume is exemplified in the following description and illustrated in the accompanying drawings, in which—

Fig. 1 shows a vertical cross section of a machine embodying my invention.

Fig. 2 shows a plan view of the bed of the machine and under portion of the carriage.

Fig. 3 shows a side elevation of the machine; and

Fig. 4 shows a longitudinal, vertical section through the bed and carriage.

The machine in its present form includes a bed 10 and a carriage 11 mounted for travel upon the bed. Preferably the carriage is provided with a number of supporting and driving shafts 12 having rollers 13 at each end operated by rails 14 at opposite sides of the bed. These shafts are driven from a motor 15 mounted upon the carriage through suitable driving connections, which connections preferably include a change speed gearing 16.

Arranged upon the bed of the machine are holding frames 17 formed of spaced plates to receive between them studding elements 18. These studding elements preferably are similar to those shown in my application, Serial No. 537,736, filed February 20th, 1922, being in the form of channels

having a series of prongs 19 projecting outwardly at one side thereof. The holding frames 17 are arranged at the desired distances apart, there being four sets of such frames shown in the present instance. The studding elements are placed in these frames so that their prongs project upwardly above the sides of the frame.

Upon the carriage I arrange a plurality of roller shafts 20, the front one carrying a series of recessed or grooved rollers 21, one overlying each holding frame, and the rear shaft 20 is provided with a series of flat rollers 22, one overlying each holding frame. Also fixed upon the carriage are standards 23 to receive a spindle 24 upon which is wound a long strip of metal lath 25.

In the operation of the machine the carriage is positioned at one end of its supporting bed and the channel-shaped studding elements are then placed in their holding frames. The loose end of the metal lath is now fastened to the ends of the studding elements immediately in front of the carriage and the carriage is driven forwardly through its motor and driving connections. As the carriage moves forwardly the metal lath is unwound and the rollers 21 on the front shaft 20 will act to press the metal lath firmly against the studding elements, the recesses or grooves therein being preferably of a sufficient depth to clear the projecting prongs, as shown in Fig. 1. The rear shaft 20 with the flat rollers will act to bend the prongs so as to fasten the lath in place upon the studding elements, as shown in Fig. 4. If desired, I may provide additional rollers so as to bend the prongs in two or more stages of operation. When the carriage reaches the end of its travel the strip of lath already laid is severed from the roll and the carriage is then returned.

Preferably I provide the carriage with a set of rollers 26 at each side working against the under side of the rails 14, which rails preferably are in the form of channels. Thereby the carriage is held upon its track and is prevented from rising upwardly when the bending rollers strike the prongs.

Various changes in the construction and arrangement of the several parts herein shown and described may be employed without departing from the spirit of my invention as disclosed in the appended claims.

Obviously, the frame which carries the roll of wire lath may be made stationary and the

table which carries the channels or studding elements may be made movable, so that the movement of the studding elements will cause the wire lath to be unwound and laid down in the required manner over the projecting prongs.

Having thus described my invention, what I claim and desire to secure by Letters Patent is:

- 10 1. A machine for assembling metal lath upon a prong studding comprising a bed, a traveling carriage upon the bed, means on the bed to receive and hold the studding elements with the prongs extending upwardly and means upon the carriage to bend the projecting prongs.
- 15 2. A machine for assembling metal lath upon prong studding comprising a bed, a traveling carriage upon the bed, means on the bed to receive and hold the studding elements with the prongs extending upwardly, means upon the carriage to bend the projecting prongs, and a motor on the carriage to drive the same.
- 20 3. A machine for assembling metal lath upon prong studding comprising a bed, a traveling carriage upon the bed, means on the bed to receive and hold the studding elements with the prongs extending upwardly, means on the carriage to press the metal lath firmly against the studding elements and means on the carriage to bend the projecting prongs after the lath has been put in place.
- 25 4. A machine for assembling metal lath upon prong studding comprising a bed, a traveling carriage upon the bed, a motor upon the carriage to drive the same, means on the carriage to support a roll of metal lath, means on the carriage to press the metal lath down upon the studding elements and other means to bend the projecting prongs after the metal lath has been put in place.

5. A machine for assembling metal lath upon prong studding comprising a bed having holding frames for the studding elements, rails at each side of the bed, a carriage, rollers on the carriage operating upon said rails, a motor on the carriage operatively connected with said rollers, front and rear shafts upon the carriage, the front one being provided with grooved rollers overlying holding frames for pressing the lath down upon the studding elements, and the rear shaft being provided with rollers to bend the projecting prongs after the lath has been put in place.

6. A machine for assembling metal lath upon prong studding comprising a bed having holding frames for the studding elements, rails at each side of the bed, a carriage, rollers on the carriage operating upon said rails, a motor on the carriage operatively connected with said rollers, front and rear shafts upon the carriage, the front one being provided with grooved rollers overlying holding frames for pressing the lath down upon the studding elements, the rear shaft being provided with rollers to bend the projecting prongs after the lath has been put in place, and means on the carriage engaging the under sides of the rails to prevent the carriage from being lifted therefrom.

7. A machine for assembling metal lath on prong studding comprising a bed, means on the bed to receive and hold the studding elements with the prongs extending upwardly, a frame to support a roll of metal lath overlying the studding elements, said frame and bed being relatively movable to cause the metal lath to be unwound and laid over the studding elements with the prongs projecting through the openings in the metal lath.

CORNELIUS COLLINS.
